PICTURE HANGER

Frederick L. Koehler, Tenafly, N. J.

Application April 3, 1931. Serial No. 527,442

2 Claims. (Cl. 40—145.1)

The invention relates to a picture hanger and in certain of its aspects aims to provide a simple and economical hanger which may be readily attached to mouldings, or to nails, screws, etc. 5 driven into the wall.

Another object of the invention is to provide a simple and convenient way of attaching an ornament to the hanger.

Further objects of the invention will be in part 10 obvious and in part specifically referred to in the description hereinafter contained which, taken in conjunction with the accompanying drawing, discloses a preferred embodiment of the invention; such embodiment, however, is to be 15 considered as merely illustrative of its principles. In the drawing—

Fig. 1 is a perspective view of a picture hanger constructed in accordance with the invention.

Fig. 2 is a front view of a picture hanger generally similar to the one shown in Fig. 1 but modified in certain respects as hereinafter described.

Fig. 3 is a side view showing an ornament overlying the hanger, and also showing in dotted 25 lines a push pin type of hook in combination with which the present type of hanger is adapted to be used if desired.

Fig. 4 is a side view showing another way in which the said picture hanger may be used in 30 combination with the type of hook shown in Fig. 3.

Fig. 5 is a side view showing the hanger used in connection with a nail or the like extending out from the wall.

Fig. 6 is a rear view of an ornament adapted 35 to be used in conjunction with the hanger shown in Figs. 1 to 5.

In the particular form of the invention which 40 is illustrated, the picture hanger is made of one piece of metal, shaped to provide a moulding-engaging hook 1 at its upper end, and a cord-engaging hook 2 at its lower end, the portion 3 of the hanger which is between said hooks being substantially plane.

When used upon a wall having a moulding, 45 the hook 1 will be engaged with the latter in the usual way; in order to adapt the hanger for use upon walls where a moulding is not available, I provide its lower end portion 4 which extends 50 upwardly from the hook 2, with a hole 5 which is located somewhat below the corresponding end edge, and thereby providing a wall 6 between the opening 5 and the corresponding end of the hanger, against which a screw, nail or the like, 55 may engage, to hold the hanger in position

against the wall from which the nail extends, with the cord-receiving hook 2 located beneath the opening 5, and the hook 1 resting against the wall above opening 5 as shown in Fig. 5.

I prefer to provide the hook portion 1 of the 60 hanger with an elongated slot 7 slightly spaced from and extending substantially parallel to the upper end edge of the hanger, to enable the slot 7 to be engaged with and supported by known 65 types of push-pin hooks or supports, in the manner shown in Fig. 3. As an alternative method of associating a picture hanger with the above 70 mentioned known types of hook, or with nails driven at an angle into the wall, the hook 1 preferably is also provided with a nail hole 8 located in the bend of the hook and adapted to 75 receive a nail (and a push-pin hook if desired) as shown in Fig. 4.

An ornamental button, rosette or the like 9, 80 may be provided to overlie the parts of the picture hanger above described, this ornament being provided with a fastening member 10 which may be an ordinary staple adapted to slidably 85 enclose the intermediate portion 3 of the latter. In the form of the invention shown in Figs. 1 and 3 the intermediate portion 3 of the hanger is provided with a struck-out ledge 11 upon which the fastening member 10 rests when in operative position. To place the ornament 9 in operative position the latter and its fastening member 10, may be engaged with the 90 hooked end portion 1 of the hanger and slid along the same until the member 10 rests upon ledge 11, as shown in Fig. 3.

Fig. 2 shows a somewhat modified construction 95 wherein the upper portion of the hanger is somewhat narrower than the lower portion, to provide shoulders 12 on opposite sides of the intermediate portion 3 of the hanger, whereby the ornament 9 and fastening member 10 may be engaged with the hook as above described, and slid along the intermediate portion 3 of the hanger until the fastening member 10 rests upon shoulders 12.

As shown in Fig. 6 a cord 13 and tassel 14 100 may be attached to the ornament 9 by engagement with fastening member 10, whereby the ornament with its fastening member, cord and tassel become a unitary article of sale. The cord 13 will not prevent the ornament from 105 being secured to the hanger as above described.

This application contains certain subject matter in common with my prior application, Serial Number 511,288, filed January 26, 1931 entitled 110 "Picture hanger".

While certain specific embodiments of the invention have been described it should be understood that changes may be made therein without departing from the invention, as set forth in the appended claims.

5 I claim:

1. A picture hanger having a moulding-engaging hook at its upper end and a cord-engaging hook at its lower end, the portion of 10 the hanger between said ends being provided with a ledge, and an ornament adapted to overlie said hanger, having a fastening member enclosing the intermediate portion of the hanger, said fastening member being slidable along the

upper portion of the hanger past the end of the hook and adapted to seat against said ledge to hold the ornament in position.

2. A picture hanger having a moulding-engaging hook at its upper end and a cord-receiving hook at its lower end, an ornament having a staple secured thereto, said staple enclosing the intermediate portion of the hanger and being slidable along the end of the hook and upper portion of the hanger to operative 85 position on the hanger, and a stop for holding said ornament in operative position overlying said hanger.

FREDERICK L. KOEHLER.
